CLAIM

The ornamental design for a holder for a paint container, as shown and described.

DESCRIPTION

FIG. 1 is a side view of a holder for a paint container showing our new design; with all remaining sides thereof appearing the same;

FIG. 2 is a top plan view thereof;

FIG. 3 is a bottom plan view thereof;

FIG. 4 is a cross sectional side view thereof; and,

FIG. 5 is a top perspective view of our new design as it would appear in use on a step ladder.

The broken line portions of the drawings are for illustrative purposes only and form no part of the claimed design.

FIG. 1

FIG. 3

FIG. 4

FIG. 5
